FLOCKED VOILE FABRIC OR THE LIKE

Monroe M. Messing, Lawrence, N. Y.

Application July 18, 1955, Serial No. 36,991

Term of patent 14 years

(Cl. D92—1)

Fig. 1 is a full scale view of a flocked voile fabric showing my new design. The ornamentation is continuously applied to one margin as shown, a single repeat being defined by the dot and dash lines on the drawing, the balance of the fabric being plain and unornamented, as indicated by the broken lines at the top of the figure.

I claim:

The ornamental design for flocked voile fabric or the like, substantially as shown and described.
